DESIGN FOR A PADLOCK.

47,239.

Specification for Design.

Patented Apr. 13, 1915.

Application filed February 18, 1914. Serial No. 819,582. Term of patent 14 years.

To all whom it may concern:

Be it known that I, **ALBERT A. PAGE**, a citizen of the United States, residing in East Haven, county of New Haven, State of Connecticut, have invented a new, original, and ornamental Design for a Padlock, of which the following is a specification when taken in connection with the accompanying drawing.

In the accompanying drawing, Figure 1 is a front elevation of a padlock embodying my design; Fig. 2 is an end elevation of the same; Fig. 3 is a top plan view; and Fig. 4 is a bottom plan view.

In my new design, the padlock body is of

flattened rectangular shape, and the edges of said body are relatively sharp, the end, top and bottom surfaces being substantially flat, and the side surfaces each being provided with a well defined central vertical rib beveled off at the top, the beveled portion being of less width than the body.

What I claim is:

The ornamental design for a padlock substantially as shown and described.
